US00D890068S

(12) **United States Design Patent** (10) **Patent No.:** **US D890,068 S**
Junghans (45) **Date of Patent:** **** Jul. 14, 2020**

(54) **VEHICLE WHEEL, TOY VEHICLE WHEEL, AND/OR REPLICAS THEREOF**

(71) Applicant: **Bayerische Motoren Werke Aktiengesellschaft**, Munich (DE)

(72) Inventor: **André Junghans**, Pfaffenhofen an der Ilm (DE)

(73) Assignee: **Bayerische Motoren Werke Aktiengesellschaft**, Munich (DE)

(**) Term: **15 Years**

(21) Appl. No.: **29/688,407**

(22) Filed: **Apr. 22, 2019**

(30) **Foreign Application Priority Data**

Oct. 24, 2018 (DE) 40 2018 101 080

(57) **CLAIM**

The ornamental design for a vehicle wheel, toy vehicle wheel, and/or replicas thereof, as shown and described.

DESCRIPTION

FIG. 1 is a perspective view of a vehicle wheel, toy vehicle wheel, and/or replicas thereof according to the design;

FIG. 2 is an additional perspective view thereof;

FIG. 3 is an additional perspective view thereof;

FIG. 4 is a front view thereof;

FIG. 5 is a rear view thereof in a lighter gray scale, representing environmental features that form no part of the claimed design; and,

FIG. 6 is a side view thereof.

1 Claim, 6 Drawing Sheets
